UNITED STATES. PATENT OFFICE.

PAUL CHORIER, OF PARIS, FRANCE, ASSIGNOR TO JOSEPH WILD & CO., OF NEW YORK, N. Y.

DESIGN FOR A CARPET-PATTERN.

Specification describing part of Design No. 5,775, dated April 16, 1872.

Specification describing a new and original Design for a Carpet, invented by PAUL CHORIER, of Paris, department of the Seine, Republic of France.

The photographic illustration fully represents my invention.

This invention relates to a new medallion-shaped center figure for carpet designs, said figure containing within an oval floral wreath a bouquet of roses. The invention also consists in arranging under the larger a smaller oval at right angles thereto, as shown.

I claim as my invention—

1. The design for the medallion-shaped figure in a carpet, as shown.
2. The combination of the smaller oval at right angles to the larger, as shown.

Witnesses: PAUL CHORIER.
